BALLAST WORKING IMPLEMENT

Corwill Jackson, Ludington, Mich.

Application June 21, 1939, Serial No. 280,294

10 Claims. (Cl. 104—13)

This invention relates to improvements in ballast working implements.

The main objects of this invention are:

First, to provide a novel implement for use in

5 railway track maintenance.

Second, to provide a vibrating implement of the type described, which is especially intended for the ready insertion of the working blade thereof beneath loose railway ties particularly 10 when the ballast in the tie crib is tightly cemented due to the accumulation of coal dust, cinders, clay and the like.

Third, to provide an implement of the type described having a ballast working blade provided with means for facilitating the penetration 15 thereof into tightly cemented ballast and the subsequent working or tamping and compacting of ballast in voids beneath the ties.

Fourth, to provide an implement of this class 20 which is highly efficient in tamping ballast under the part thereof directly below the rail.

Objects relating to details and economies of the invention will appear from the description to follow. The invention is defined in the claims.

25 Preferred embodiments of the invention are illustrated in the accompanying drawing, wherein:

Fig. 1 is a perspective view illustrating the implement of this invention and one manner of using the same in track maintenance work.

Fig. 2 is a fragmentary view illustrating a railway track and tie and one manner of manipulating the implement of the invention to tamp ballast under a tie directly beneath the rail, successive manipulations of the implement being illustrated in dotted and full lines.

Fig. 3 is a fragmentary view in elevation, still further illustrating the action of the implement in use.

40 Figs. 4 and 5 are fragmentary views illustrating modified types of blades contemplated for the implement of the invention.

Fig. 6 is a perspective view illustrating an implement digging and tamping blade in accordance 45 with this invention employed in connection with a modified form of vibratory mechanism therefor.

Of recent years efforts have been made by railroads to reduce the size of track maintenance 50 gangs to a minimum and it has been found that three men is about the irreducible number for such a gang and still be reasonably efficient. The duties of these track maintenance gangs is to make minor tie renewals and principally to 55 retamp loose ties and reposition and tamp low ties. The present invention concerns an implement having novel provisions for enabling its ready insertion in ballast which has become tightly cemented due to accumulation of coal dust, cinders, clay and other foreign matter in

the tie crib to enable the blade to reach and compact ballast into voids beneath the ties or tamp in additional ballast. Since these voids may be 5 relatively small and still have an objectionable effect, the blade is preferably quite thin yet has sufficient rigidity for the loosening and tamping functions which it is intended to perform and furthermore the blade has a digging or penetrating point and suitable tamping edges for facilitating entry thereof into cemented ballast and 10 for urging the ballast forwardly into the void and into position to effectively support the rails.

Referring to the drawing, I illustrate an implement well adapted for the aforesaid functions or uses, the implement consisting of, in the preferred embodiment of the invention, a supporting and vibratory mechanism generally indicated 15 similar to that illustrated in my Patent No. 2,137,842, dated November 22, 1938, and a working or digging and tamping blade which is generally indicated 2. The vibratory mechanism and support is made up of a handle 21 connected to a frame 3 which carries an adjustable flexible belt 4 supporting the vibratory element 5 which in the illustrated embodiment includes a vibratory motor having a rotating eccentric or unbalancing weight (not shown) whereby rotation of the motor causes high frequency vibrations to be imparted to the motor housing. The blade 2 is removably bolted at 6 to the motor housing, 20 being in the illustrated embodiment disposed transversely of the motor axis.

The blade is made of spring sheet steel approximately $\frac{3}{16}$ inch thick and of a suitable width to perform the functions to be described. It is off-set or angled at 61 to enable its ready positioning approximately horizontally parallel to the ground if desired, and has a forwardly disposed digging or penetrating point 7 at one side thereof, being inclined rearwardly on the forward portion of 40 its other side edge and provided with a plurality of tamping steps or shoulders 8 in the thus inclined side edge.

In Figs. 4 and 5 I illustrate modified embodiments of the blade of the invention, characterized 45 by the fact that the forward digging or penetrating point 71 is disposed centrally of the blade, which is angled or inclined rearwardly at either side of the penetrating point, the steps or shoulders in the inclined sides being indicated by the 50 reference numeral 81. The difference between the embodiments of Figs. 4 and 5 is that in the former the penetrating point 71 has a sharp nose and in the latter it has a curved or rounded nose. Likewise, in Fig. 5 the steps 81 are inclined slightly 55 to the rear instead of being normal to the axis of the blade and point 71 as in Fig. 4. Functionally, however, these two modifications are in general equivalents and, moreover, they are functionally similar to the embodiment of Figs. 1, 2, 60

and 3, in that the point 7 or 11 readily enters tightly cemented ballast in the manner of a spear or pick during the initial operation, while the steps or shoulders 8, 81 trap a certain amount of ballast against the blade and cause it to be forced in a general downward and inward direction in relation to the tie to fill the void therebeneath—for example, see the manipulation illustrated in Fig. 2. In using the implement as illustrated in Figs. 1, 2 and 3, the ballast is first suitably loosened and the implement then inserted downwardly and inwardly relative to the ballast at a given point, then successively inserted at points proceeding outwardly toward the tie end so that the ballast will be uniformly distributed in any previously existing void beneath the tie or suitably compacted beneath the tie. Successive positions of insertion of the tool are illustrated in solid and dotted lines in Fig. 2.

In Fig. 6, I illustrate a modified embodiment of the invention wherein the blade 2 is employed in connection with a percussive device such as a pneumatic tamper, the blade being fitted to a shank 9 to which percussive blows are delivered in housing 10 through the pneumatic line 11. This device is generally similar to that illustrated in my Patent No. 1,747,939, dated February 18, 1930. If desired, the blade according to my invention may also be utilized with a vibratory tamper of the unbalanced weight type illustrated and described in my Patent No. 2,080,921, dated May 18, 1937, or in connection with a mechanism of the vibratory impact type in which a series of blows are imparted by a suitable rotary member to the end of the blade holder or stem as illustrated in my Patent No. 2,025,287 of December 24, 1935.

The blade 2, as will be apparent from the above, may be disposed either parallel to or transverse to the shaft of the vibratory or reciprocating tamping mechanism.

I have illustrated and described my improvements in embodiments which are very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. In a vibratory ballast working implement a flat relatively thin blade terminating at its forward end in a pointed digging member adapted to readily enter compacted or cemented ballast and being inclined rearwardly from said member on at least one side thereof, there being a plurality of stepped abutments on the inclined portion of the blade providing ballast tamping shoulders adapted to trap ballast against the blade and force the same forwardly.

2. In a vibratory ballast working implement a blade terminating at its forward end in a relatively thin, flat digging member adapted to readily enter compacted or cemented ballast and being inclined rearwardly from said member on at least one side thereof, there being a plurality of stepped abutments on the inclined portion of the blade providing ballast tamping shoulders adapted to trap ballast against the blade and force the same forwardly.

3. In a vibratory ballast working implement a flat relatively thin blade terminating at its for-

ward end in a centrally disposed pointed digging member and being inclined rearwardly from said member on both sides thereof, there being a plurality of stepped abutments on said inclined portion providing ballast tamping shoulders adapted in use to trap ballast against the blade and urge the same forwardly and laterally of the blade.

4. In a vibratory ballast working implement, a blade terminating at its forward end in a relatively thin centrally disposed pointed digging member and being inclined rearwardly from said member on both sides thereof, there being a plurality of stepped abutments on said inclined portion providing ballast tamping shoulders adapted in use to trap ballast against the blade and urge the same forwardly and laterally of the blade.

5. In a vibratory ballast working implement, a tool carrying support and a tool on said support comprising a blade terminating at its forward end in a relatively thin pointed digging member and inclined rearwardly on at least one edge from said member, there being means on said inclined portion providing ballast tamping shoulders adapted in use to trap ballast against the blade and urge ballast forwardly and laterally of the blade.

6. In a ballast working implement of the type described, a digging and tamping tool including a member having an edge terminating forwardly in a digging element and inclined rearwardly of said element and provided with abutment members adapted to tamp aggregate penetrated by said element and carry said aggregate forwardly and laterally into a void beneath a railroad tie.

7. A ballast working implement of the type described, comprising a digging and tamping tool including a relatively wide blade-like member terminating forwardly in a relatively thin pointed digging element adapted to readily penetrate cemented ballast and enter a narrow void beneath a tie, and having a side thereof inclined rearwardly of said element and provided with steps adapted to tamp ballast penetrated by said element and carry said ballast forward and laterally into a void beneath the tie.

8. A ballast working implement of the type described, comprising a digging and tamping tool including a relatively wide blade-like member terminating forwardly in a relatively thin pointed digging element adapted to readily penetrate cemented ballast and enter a narrow void beneath a tie, and having a side thereof inclined relatively sharply rearwardly of said element and adapted to tamp ballast penetrated by said element and carry said ballast forward and laterally into a void beneath the tie.

9. A ballast working tool comprising a handle, a relatively wide flat blade-like tool secured to the handle and having an inwardly beveled point at one edge thereof, and a plurality of steps rearwardly of said point and presenting forwardly facing faces adapted to successively engage the work as the blade is inserted therein.

10. A ballast working tool comprising a handle, a relatively wide blade-like tool secured to said handle and having a point digging element at its forward end, and a plurality of steps rearwardly of said digging element and presenting forwardly facing faces adapted to successively engage the work as the tool is inserted therein.

CORWILL JACKSON.
